UNITED STATES PATENT OFFICE.

EDWARD McCREARY, OF COHOES, NEW YORK, ASSIGNOR TO JOHN McCREARY AND EDWARD J. McCREARY, OF COHOES, NEW YORK.

MACHINE FOR TREATING BLANKETS OR FABRICS.

Application filed September 26, 1923. Serial No. 664,959.

To all whom it may concern:

Be it known that I, EDWARD McCREARY, a citizen of the United States, residing at Cohoes, in the county of Albany and State of New York, have invented new and useful Improvements in Machines for Treating Blankets or Fabrics, of which the following is a specification.

This invention relates to brushing machines for treating blankets and all classes of knitted clothing or fabrics.

The primary object of the invention is to provide comparatively simple and effective means adapted to be readily controlled or adjusted to produce a combing as well as napping action relatively to the blanket or fabric treated thereby, the nap of the blanket or fabric being raised as the latter passes between a part of the mechanism and combed out by being held in close engagement with and moving around past the said mechanism, and at the same time the blanket or fabric treated is guided to a means for carrying the same away from the improved mechanism.

The invention consists essentially of a novel arrangement of feed rolls and cylindrical brushing cylinder with which a suitable automatically yieldable pressure bar operates to maintain uniform pressure of the blanket or fabric relatively to the brushing cylinder, to accommodate various thicknesses of blankets and fabrics as well as grades of fabric and to further subject the blanket or fabric to the action of a guide roll to assist the cylinder in its function, and also to combine with the parts just specified a novel form of spiral cast-off roll having yielding spiral blades, which operate to continually sweep the surface of the brushing cylinder and prevent the ends of the blanket or fabric from catching on said cylinder.

The invention further consists in the construction and arrangement of the several parts which will be more fully hereinafter described and claimed.

In the drawings:

Fig. 1 is an end elevation of a machine embodying the features of the invention;

Fig. 2 is a longitudinal vertical section through the improved machine;

Fig. 3 is an enlarged sectional view taken through the essential parts embodying the

features of the improvement, the frame or support being omitted; and

Fig. 4 is an enlarged elevation of a portion of the spiral cast-off roll.

The numeral 5 designates the frame of the machine having an upper horizontal top portion 6 including girths 7. At the front of the top portion of the frame a feed table or other device 8 is mounted and this may be replaced if desired by the well known form of feeding belt, it being only necessary to have means for regularly guiding the blankets and fabrics to be treated to the mechanism of the machine, and it will be understood that any suitable means may be used for this purpose. In rear of the feed table or analogous device 8 is a pair of feed rolls 9 and 10 mounted in suitable bearings with the roll 9 superposed with relation to the roll 10, the roll 9 being preferably automatically movable or having a gravitating action relatively to the roll 10, as in similar feed roll constructions. The rolls 9 and 10 are intergeared or respectively have meshing pinions 11 and 12 at their ends, to rotate the said rolls in the proper direction for delivering the blankets or fabric fed thereto towards the remaining mechanism. At a suitable distance in rear of the feed rolls are longitudinally adjustable bearings 13, which are arranged to be shifted by a screw 14 and a rod 15 adapted to have a hand wheel 16 applied thereto, as shown by dotted lines in Fig. 1, the screw and rod respectively having meshing gears 14^a and 15^a. The bearings 13 will be duplicated on opposite sides of the frame and therein a shaft 17 is rotatably mounted and carries a wire brushing or napping cylinder 18, as clearly shown by Figs. 2 and 3. By adjusting the bearings 13, the shaft 17 and cylinder 18 may be shifted forwardly or rearwardly as desired for the purpose of treating blankets or other fabrics of varying thicknesses.

Between the lower roll 10 and the brushing or napping cylinder 18 a suitable pressure bar 19 is mounted and may be similar to that disclosed by Patent No. 1,400,446, issued to J. and E. J. McCreary, December 13, 1921. This pressure bar is preferably curved and stands or is held in an operative position at a suitable distance in advance of the brushing or napping cylinder 18. The

bar is of concavo-convex contour with the convex side 20 thereof facing the cylinder 18, the thicker portion of the bar being towards its lower edge and the thickness of 5 the bar gradually diminishing towards its upper edge.

Below the feed rolls 9 and 10 and in advance of the brushing and napping cylinder 18 a guide roll 21 is mounted and is suitably operated from the remaining mechanism to rotate in the direction of the arrow shown by Fig. 2, or in a direction reverse to the rotation of the brushing and napping cylinder, which also has an arrow indicating the direction of rotation thereof applied to the same. The guide roll 21 is covered with a suitable fabric 22 over which the blanket or fabric to be treated can easily pass, and the function thereof is to direct 10 or guide the blanket or fabric treated around the brushing and napping cylinder, so that the latter itself may comb out the nap. The guide roll 21 is located very close to the lower portion of the brushing and 15 napping cylinder 18 and at a distance below the pressure bar 19, to give the said cylinder wires engagement with a large portion of the blanket or fabric as compared to similar machines heretofore devised and as shown, 20 for instance, by Patent No. 1,400,446, hereinbefore noted.

Directly beneath the shaft 17 of the brushing and napping cylinder 18 a spiral cast-off roll 23 is mounted and consists of a 25 shaft 24 extending through the frame and suitably operated from the remaining mechanism to rotate in the direction of the arrow as shown by Fig. 2. Extending outwardly from the shaft 24 are radial supports or arms 25 secured to hubs or collars 26 fixed to the shaft 24 at regular intervals and so disposed in angular relation as to accommodate the arrangement of spiral blades 27 extending longitudinally and regularly around the cast-off roll, these blades being constructed of material suitable for the purpose and in the form of strips of suitable width. The edges of the blades 27 are primarily disposed in such relation to 30 the lower portion of the brushing and napping cylinder 18 that they continually sweep the wire clothing or other combing and napping surface covering of the said cylinder and prevent the ends of the blankets 35 or fabrics, which are successively treated by the said cylinder 18, from following the latter and catching on themselves.

Below the guide roll 21 and cast-off roll 23 and extending lengthwise through the 40 frame towards the front end or adjacent to the front end of the feed table or device 8 is a return carrier 28, consisting of an endless belt of suitable construction trained over front and rear rolls 29 and 30, respectively having shafts 31 and 32 held in

suitable bearings at opposite parts of the frame and driven in timed relation to the mechanism above. The purpose of this carrier 28 is to receive the blanket or fabric after it has been subjected to treatment and 45 convey the said blanket or fabric out through the front of the machine, where it may be readily reached by an operator.

Incidentally and as a matter of convenience and advantage, the mechanism embodying the essential features hereinbefore specified is shown as provided with a hood 33 thereover, which encloses the feed rolls 9 and 10 as well as the brushing and napping cylinder 18, the said hood having at the 50 front 34 a feed opening 35, to expose the rolls 9 and 10. Around the rear end of the frame and over the bottom thereof is also shown a sheet metal wall or plate 36, which forms a partial enclosure, the front of the 55 frame being left open for the projection of the return carrier 28, as shown by Figs. 1 and 2. The hood 33 and enclosing wall or sheet 36 serve to confine any lint that may be thrown off of the blanket or fabric within 60 the body of the machine. This hood and sheet wall structure is not necessary to the practical operation of the essential features of the invention as hereinbefore described but, as above noted, are advantageous accessories.

The parts of the machine are started by suitable control mechanism and the blanket or fabric to be treated is placed on the table or other device 8 and pushed forward to, 65 and engaged by, the rolls 9 and 10 and carried between the latter over the convex side 20 of the pressure bar 19 and brought into contact with the brushing and napping clothing of the cylinder 18, and then passed 70 around the guide roll 21 and the free extremity thereof falls to and is engaged by the upper portion of the carrier or endless belt 28 and moved forwardly towards and out through the front end of the machine, 75 where it may be readily reached and withdrawn from the machine. Should the end of the blanket or fabric cling to the clothing of the cylinder 18, it will be thrown off and forwardly by the blades 27 of the 80 castoff roll 23 and fall to the carrier or endless belt 28, as above specified.

The improved machine will be found exceptionally advantageous in the brushing and napping of blankets or fabrics generally, and it will be understood that changes in the general construction and arrangement of the several parts may be adopted as fairly fall within the scope of the appended 85 claims.

What is claimed as new is:

1. In a blanket or fabric brushing and napping machine, the combination with a brushing cylinder, feed rolls and a pressure bar between the feed rolls and cylinder de- 90

pending in advance of the cylinder, of a single guide roll set in close to the lower portion of the brushing cylinder below the pressure bar to maintain a considerable length of the blanket or fabric in engagement with the brushing cylinder, a cast-off roll with spiral blades in continual engagement with the lower portion of the brushing cylinder to prevent adherence of the blanket or fabric end with the cylinder, and a conveying means for transferring the treated fabric outwardly through the machine.

2. In a blanket or fabric brushing or napping machine, the combination with a brushing cylinder, rolls for feeding a blanket or fabric to the cylinder and a rigid pressure bar depending in advance of the cylinder and between the latter and the feeding rolls, of a single guide roll disposed below the feeding rolls and pressure bar and the front portion of the brushing cylinder, the single guide roll being located mainly in rear of the said feeding rolls and pressure bar and close to the lower portion of the cylinder, the said single guide roll having the blanket or fabric solely engaging the rear and a part of the under portion thereof adjacent to the brushing cylinder to hold a relatively greater portion of the blanket or fabric between the said pressure bar and the rear portion of the said guide roll in close engagement with the front portion of the brushing cylinder to operate on a greater length of the blanket or fabric, the convey-

ing means having movement towards the front of the machine and disposed below the said single guide roll for receiving the treated blanket or fabric directly from the guide roll and transferring said blanket or fabric outwardly towards and through the front of the machine.

3. In a blanket or fabric brushing or napping machine, the combination with a brushing cylinder, a set of feed rolls and a rigid pressure bar interposed between the feed rolls and cylinder, of a single guide roll below the feed rolls and pressure bar and close to and in advance of the lower portion of the brushing cylinder to hold a considerable length of the blanket or fabric between the pressure bar and the said guide roll in close engagement with the brushing cylinder and also for directing the treated blanket or fabric downwardly below the said guide roll, a cast-off roll disposed directly below the brushing cylinder and having elongated spiral blades in continual engagement with the brushing means of the cylinder to prevent the blanket or fabric from catching and being held on the cylinder, and a conveying means below the guide and cast-off rolls for receiving the treated blanket or fabric and transferring the latter out through the machine.

In testimony whereof I have hereunto set my hand.

EDWARD McCREARY.
